UNITED STATES PATENT OFFICE

167,436

BIRD CAGE

Edward Yellin, Chicago, Ill., assignor to Bernard Edward Co., Chicago, Ill., a corporation of Illinois

Application May 31, 1952, Serial No. 19,965

Term of patent 7 years

(Cl. D31—2)

To all whom it may concern:

Be it known that I, Edward Yellin, a citizen of the United States, and a resident of the city of Chicago, county of Cook, State of Illinois, have invented a new, original, and ornamental Design for Bird Cage, of which the following is a specification, reference being had to the accompanying drawing, forming a part thereof in which:

Figure 1 is an isometric view of a bird cage, showing my new design and showing the details of design of the top, one end, and one side thereof.

Figure 2 is an elevation view of the far end thereof.

Figure 3 is an elevation view of the hidden side thereof and is taken looking from the right of Figure 2.

The dominant features of my design reside in those portions shown in full lines.

I claim:

The ornamental design for a bird cage, as shown and described.

EDWARD YELLIN.
